UNITED STATES PATENT OFFICE.

EDWARD R. NORMAN, OF CHICAGO, ILLINOIS.

PISTON-RING.

1,367,710.

Specification of Letters Patent.

Patented Feb. 8, 1921.

Application filed July 9, 1917. Serial No. 179,297.

To all whom it may concern:

Be it known that I, EDWARD R. NORMAN, a citizen of the United States, residing at Chicago, in the county of Cook and State of Illinois, have invented certain new and useful Improvements in Piston-Rings, of which the following is a specification, reference being had therein to the accompanying drawing.

10 This invention relates to one-piece expansive piston rings, which may be used in various organizations, as for example on pistons of different kinds of engines.

The primary object of my invention is to 15 provide a one-piece self-expansive ring having certain features whereby the inner tongues of the joint are radially thicker than their associated outer shoulders to give greater strength and durability to the joint, 20 and the joint ends are made up of curves so they do not have any square shoulders that weaken the ring and the liability of the tongues being broken in springing the ring into position is eliminated. Other objects 25 will be apparent from the disclosure.

My expansive one-piece piston ring and the process of making the same are illustrated in the accompanying drawings wherein—

30 Figure 1 shows a side view of the original blank from which the ring is made;

Fig. 2 is a view showing the operation of milling one side of the joint as by a top cutter or milling tool;

35 Fig. 3 is a view showing the operation of milling the other side by a lower cutter or miller, and showing parts for the joint as completed by the operation of the cutters;

Fig. 4 is a detail side view of the ends 40 when the joint is closed;

Fig. 5 is a detail plan view of the ends with the ring in closed position;

Fig. 6 is a detail plan view of the blank after the parts of the joint are cut;

45 Fig. 7 is a side view of the ends of the ring in distorted position showing the first step in the fatiguing process;

Fig. 8 is a side view of the ends of the ring at different positions during the fatiguing 50 process, and

Fig. 9 is a diagrammatic view.

In forming my self-expanding one-piece ring by my process I first produce by cast-

ing or otherwise a ring shaped blank B of suitable material, such as gray iron. The 55 shape of this blank is slightly eccentric; the right-hand half of the blank is made on a radius struck from the position x, and the left-hand half is made on a radius struck from the position y, the center of the blank 60 being at z; by this arrangement one (here the vertical) diameter of the blank is shorter than that at a right angle (here the horizontal diameter), and the joint is cut at either end of this shorter diameter of the blank or 65 casting as at b, all as shown in Fig. 1. The blank in its size exceeds that of the finished ring in closed position by an amount equal to the amount of material removed at the joint to properly make the joint plus shrinkage 70 and the amount allowed to properly finish the periphery of the ring. The width of the blank should exceed that of the finished ring by allowing for shrinkage and machining or grinding. The joint is cut on 75 the shorter diameter of the blank as shown in Fig. 1, with a suitable cutter or milling tool. In cutting the joint the inner tongues are made with greater radial thickness than their associated shoulders; the radial thickness of the tongues may be anything greater than that of the shoulders but in practice I prefer to make them on the ratio of 3 to 2. Preferably the blank is placed in a fixed position, and a revolving upper cutter moves 80 from position A' toward the center of the blank at a suitable point at one side of the dividing line b to position at A² in Fig. 2, cutting a round notch N in the outer face of the blank to a width equal to one-half of the 85 width of its outer face or periphery and to a depth equal to two-fifths of its radial thickness; the cutter then moves laterally to position A³ cutting a curved recess R on the same radius as the ring at the joint and 90 forming a tongue T, which is three-fifths of the radial thickness of the blank, and then moves from A³ to A⁴ laterally and inwardly cutting a round end or tip on the tongue, and then moves from A⁴ laterally through 95 A⁵ to A⁶ leaving a cheek, and from A⁶ to A⁷ laterally and inwardly cutting a round end or tip two-fifths of the radial thickness of the blank and one-half its width corresponding with the first operation, and from A⁷ 100 to A⁸ laterally to A⁹ cutting a

curved recess R' on the same radius as the ring at the joint and forming a shoulder S which is two-fifths of the radial thickness of the blank and having a round notch N' . 5 This completes its operation and the cutter then moves to A' . The blank is then symmetrically milled or cut away on the opposite side of the dividing line, the operation being similar to the first. The operations 10 may be either simultaneous or separate as desired. In the present instance I employ a lower cutter which moves from position B' toward the center of the blank to position B^2 , cutting a round notch N^2 in the outer 15 face of the ring to a width equal to one-half of the width of its outer face and to a depth equal to two-fifths of its radial thickness; the cutter then moves laterally to B^3 cutting a curved recess R^2 on the same radius as the 20 ring at the joint and forming a tongue T' which is three-fifths of the radial thickness of the blank, and then moves from B^3 to B^4 laterally and inwardly cutting a rounding end or tip on the latter tongue, then from 25 B^4 through B^5 to B^6 leaving a cheek, and from B^6 to B^7 cutting laterally and inwardly to form a rounded end or tip, and from B^7 to B^8 cutting a curved recess R^3 on the radius of the ring at the joint and forming 30 a shoulder S' which is two-fifths of the radial thickness of the blank and having a round notch N^3 . This completes the operation and also results in severing the blank at the line b . 35 The tongues are on the inner side of the ring, the shoulders being on the outer side where they bear against the cylinder walls when the ring is mounted on the piston. The depth or radial thickness of the tongues 40 is three-fifths of the depth of the ring at the joint, and the shoulders are two-fifths of the ring's depth. By making the tongue radially thicker than its coöperating shoulder, the liability of the tongue to break or 45 snap off is obviated. When the tongues and shoulders are of the same radial thickness the former are weaker than the latter as they are merely reduced tips projecting beyond the body of the ring, while the shoulders 50 are formed by merely undercutting the body and so have the support afforded along one entire side by the lateral metal of the body to strengthen them. When these parts are so made the inner tongues are apt to 55 break when the ring is compressed for insertion in the cylinder and also after it has been used; when the ring is compressed to insert it in the cylinder the strain on the tongue is sudden and great, and after the 60 ring is in place the pressure on the extended or prolonged tongue tends to snap it off, this latter tendency increasing as the rings expand in use or in oversize cylinders by reason of the stress or strain moving away from 65 the base of the tongue and increasing more

and more toward its end, while in both these relations the outer shoulder is confined and backed by the cylinder wall and so is additionally strengthened. By reducing the radial thickness of the shoulder its liability 70 to break is not increased owing to the fact that it is always strengthened by the lateral metal of the body and backed by the cylinder-wall, and by transferring a corresponding amount of metal to the inner tongue by 75 increasing its radial thickness it is in turn strengthened and its liability to break off is obviated. The round notches are important as they give strength to the tongue by making it wider at its base, and help make 80 the seal. The round end or tip of the tongue and shoulder is important when placing the rings in the cylinder so that they will not catch as they slip past each other, and they also help to make the seal. The curved 85 faces of the tongues and shoulders make a surface seal with a circumferentially elongated bearing, instead of an edge or ledge seal.

After the joint is milled the sides of the ring are ground true to the desired width. The ring is then clamped in closed position and the crust on the periphery of the ring is removed by rough turning or grinding the ring to slightly larger than the finished 95 size, and the ring is then released from the clamp. After the ring is roughed slightly larger than the finished size, it is then opened as shown in Fig. 7 so that it will 100 slip over the piston into the groove of which it is to fit, and while in this position its ends are oppositely passed back and forth; one end, designated E , is moved to position 12 Figs. 8, and 9 and the other end E' , is moved to position 8 simultaneously; and then end E is moved to position 9, and end 105 E' to position 11 simultaneously. This treatment being carried out while the ring is expanded as shown at Fig. 7, sets the particles in the ring the same as if the ring 110 was sprung over a piston into the groove thereof, so that it is not deformed when finally so sprung into place.

The ring is then finished by closing the joint and clamped into a suitable holder and 115 while in this position the periphery is ground to finished size, when the ring is removed from the clamp and is ready for use.

I claim:—

1. A one-piece packing-ring having a 120 joint formed by two meeting ends, each end being cut-away to form an outer shoulder and an inner tongue on opposite sides of its median line, each tongue being of greater radial thickness than its overlying shoulder 125 and concentric therewith.

2. A packing ring having a joint comprising pairs of overlapping inner tongues and outer shoulders on the opposite sides of its median circumferential dividing line, 130

each pair of said tongues and shoulders having opposing seats extended circumferentially and providing prolonged seals on a line concentric with the curvature of the 5 ring, and each tongue being of greater radial thickness than its coöperating shoulder.

In testimony whereof I affix my signature in presence of two witnesses.

EDWARD R. NORMAN.
